UNITED STATES PATENT OFFICE.

GEOERGE B. O'CONNOR, OF NEW YORK, N. Y.

HAIR-WAVING COMB.

Application filed November 10, 1926. Serial No. 147,487.

This invention relates to combs especially adapted for use to give a crinkled or wavy appearance to the hair.

The principal object of the present invention is the production of a comb having hair engaging members which coact to produce an arrangement of strands of the hair which will present a novel crinkled or wavy appearance, the strands of the hair being grouped in piles.

The nature of the invention and its distinguishing features and advantages will appear when the following specification is read in connection with the accompanying drawings, in which—

Figure 1 is a side elevation of a comb embodying the present invention.

Fig. 2 is an edge view.

Fig. 3 is a sectional view taken on the line 20 3—3 of Fig. 1.

The comb of the present invention may be made from any preferred material, may be of any size, and may be curved, or be flat as shown in the drawing. The comb comprises 25 a back or body section 10 and hair engaging members or teeth 11. The hair engaging members 11 are similarly constructed or

shaped. The opposite side edges of the hair engaging members, excepting the two end members are irregular or are crinkled or 30 waved; each of the end members having but one side edge thereof so formed, as at 12 to provide comparatively large and small spaces 13 and 14 respectively. Each of the hair engaging members 11 terminates substantially in a point 15 to facilitate the 35 combing operations and to readily separate the hair into strands. By virtue of the provision of the hair engaging members described it is possible to obtain groups of 40 hair strands which will be piled on each other so as to give a novel wavy or crinkled appearance.

I claim:

1. A hair waving comb characterized by 45 flat hair engaging members whose opposite side edges have lateral pointed portions of uniform size and shape.

2. A hair waving comb characterized by 50 flat hair engaging members each having angular portions of uniform size and shape which provide comparatively large and small spaces between said members.

GEORGE B. O'CONNOR.
